UNITED STATES PATENT OFFICE.

FRANK BARNARD, OF LOUISVILLE, KENTUCKY.

DESIGN FOR A DOLL.

60,599.

Specification for Design. Patented Mar. 14, 1922.

Application filed November 19, 1920. Serial No. 425,286. Term of patent 3½ years.

To all whom it may concern:

Be it known that I, FRANK BARNARD, a citizen of the United States of America, and resident of Louisville, county of Jefferson, State of Kentucky, have invented a new, ornamental, and original Design for a Doll, of which the following is a specification, reference being made to the accompanying drawings, forming a part thereof.

In the drawings:

I claim:

The ornamental design for a doll as shown.

FRANK BARNARD.
